United States Patent Office

Des. 180,239

Patented May 7, 1957

180,239

HELMET

John N. McMurry, Hawthorne, Calif.

Application September 13, 1956, Serial No. 42,917

Term of patent 14 years

(Cl. D3—13)

Fig. 1 is a side elevational view of a helmet showing my new design;
Fig. 2 is a front elevational view; and
Fig. 3 is a rear elevational view thereof.
I claim:
The ornamental design for a helmet, as shown.
